UNITED STATES PATENT OFFICE.

HENRY C. TROST, OF EL PASO, TEXAS.

BUILDING CONSTRUCTION.

1,419,995.

Specification of Letters Patent. Patented June 20, 1922.

Application filed January 18, 1922. Serial No. 530,013.

To all whom it may concern:

Be it known that I, HENRY C. TROST, a citizen of the United States, and a resident of El Paso, in the county of El Paso and 5 State of Texas, have invented certain new and useful Improvements in Building Constructions, of which the following is a description, reference being had to the accompanying drawings, which form a part 10 of my specification.

My invention relates more particularly to sleeping compartments adapted to be readily applied to or constructed in a building; the invention having for its object the 15 provision of means whereby a sleeping compartment or series of compartments may be provided in the outer side wall of a building, preferably adjacent to the roof or overhanging structure, in weather-proof relation therewith and formed to be readily accessible from the room or main portion of 20 an apartment while permitting the occupant, after retiring, to manipulate the structure so as to admit air from the exterior 25 of the building, or to practically expose the entire bed to the exterior of the building while the remainder of the room or apartment may be completely closed off and draughts across the bed or the admission of 30 cold air into the main portion of the apartment or room thereby prevented.

The invention contemplates, in conjunction with a couch or bed, the provision of a wall provided with a window-frame or sash- 35 section and with one or more sliding sections; the wall with the window-sash section and the sliding section being adapted to swing as a unit toward opposite sides of the bed or couch; with the window-frame 40 and sliding sections so correlated that the inward and outward swinging movement of the wall can only be accomplished when said sections have been arranged in a predetermined relation to each other.

45 A further object of the invention is to provide a construction of the character mentioned which will be weather-proof when in complete closed position, that is to say when the wall, consisting of the respective 50 sections, has been swung outwardly where it in reality constitutes the outer wall section of the building; it being understood that the construction is more essentially adapted for use in the upper part of a building, although permitting its employment at any point in the side wall of a building.

The objects and advantages of my invention will all be more readily comprehended from the detailed description of the accompanying drawings, wherein:—

60 Figure 1 is a perspective view of a plurality of my improved sleeping compartments arranged adjacent to the roof of a building.

Figure 2 is a vertical sectional elevation 65 of my improved structure.

Figure 3 is a cross sectional view taken on the off-set line 3—3 of Figure 2 looking in the direction of the arrows.

Figure 4 is a detail sectional view taken 70 on the line 4—4 of Figure 2 looking in the direction of the arrows.

Figure 5 is a similar view taken at a point intermediate of adjacent compartments.

75 Figure 6 is a vertical sectional view of a portion of the swinging wall.

Figure 7 is a perspective view of the interior thereof.

Figure 8 is a detail view of the pivoted 80 end thereof.

Figure 9 is a detail cross-sectional view taken on the line 9—9 of Fig. 8.

Figure 10 is a detail sectional view, in perspective, of a portion of the sliding section. 85

Figure 11 is a detail view, partially in section, of the sliding portion of the swinging wall section.

Figure 12 is a perspective view of a member of the sliding portion.

90 The invention, as exemplified in the drawings, is illustrated in connection with the upper portion of a building wherein the main side wall is provided with sufficient sized opening or openings, through which 95 the floor of the adjacent room may project to a predetermined extent, if desired. My improved structure is secured in the opening so as to jut out from the main wall and it comprises suitable studs or jambs 20, at 100 each side of the opening in the wall; the jambs 20 being preferably shown in the nature of channel metal so as to provide a weight or counterbalance slide-way, see Figure 2. Secured to the jamb 20 are the end 105 walls or partitions 21, which may also be of sheet metal, such as ply-metal, or other suitable material, adapted to extend from the roof portion 22 of the structure down to the floor from a point preferably slightly 110 beneath the main roof 23 of the building, or overhanging portion of the building, as the

jambs 20 are, of course, secured to the main wall of the building.

The outer edges of the end walls or partitions 21 are provided with a jamb 24 which is also preferably made of sheet metal provided with an outwardly projecting reinforcing rib 25; the jamb 24 being formed to provide the lower vertically disposed portion 24^a, of predetermined height, and the sloping 10 or inwardly inclining portion 24^b, whereby the compartment is given greater width at the bottom to receive a bed or couch indicated at 26; the lower portions 24^a being provided with the panels or portions 27 (see 15 Figures 1 and 2), constituting a parapet or non-movable wall section. In order that my improved sleeping compartment may be made as a separate unit adapted to be built in or secured to a previously built house, I have 20 shown the main portions composed of sheet metal of suitable shapes to provide proper strength and at the same time withstand the weather. At the upper ends of the jambs 24 I show a cross-piece 28 of any suitable 25 construction, so as to provide a weather-seal for the movable or swinging wall section later to be described. The upper edge of the panel 27 of the parapet is shown provided with a sill member 29 having the upper rounded 30 edge adapted to overlap the upper edge of a bracket or rail portion 30 which may be disposed lengthwise of the compartment and may either be secured to or formed integral with the panel 27 and bent so as to have sufficient strength to support the bed 26 of usual 35 length; the sill being formed to provide a proper water-shed or joint at the lower end of the swinging wall section. The opposite side of the bed 26 is supported by a bracket 40 or rail 31, shown formed out of sheet metal to constitute not only a bed-supporting rail, but also a sill adapted to conform with and overlap the lower end of the swinging wall section, on the outer side thereof, as shown 45 at 31^a; the rail and sill extending from one jamb or upright member 20 to the other. In the construction illustrated in Figure 2, the bed is shown as removably held in place, thus permitting renovation and replacement 50 when occasion should require.

The movable wall consists of a panel portion 32 of ply-metal or other suitable material, preferably given the canopy or bowed formation, as shown more clearly in Figures 55 6 and 7, adapted to shed rain; the bowed portion being formed integral with the two sides 33, 33, which are flanged or have the bent marginal portions 34, 34 while the upper edge of the bowed portion is bent upwardly at 35 and formed integral with or secured to the marginal portions 34, 34. The side marginal portions 34, 34 are shown provided with the channel members 36, 36; the open sides whereof are preferably disposed inwardly or toward each other, see Figure 60 65

7. The lower ends of the channel members 36 are slotted longitudinally for a predetermined distance, as shown at 37, while the upper ends of said channel members are each provided with a bracket 38, suitably secured thereto and arranged to carry a pulley 39 disposed preferably on the inner adjacent sides of the channel members or rails 36 and therefore substantially in alignment with the sides of the jambs or uprights 20, 20. 70 The bowed part of the panel 32, preferably in the substantially vertical portion thereof, is provided with a window-frame as at 40, of any suitable construction for one or more glass panes, which may either be stationarily held or slideable. The upper end of each channel member or rail 36, is apertured at 41 to receive a pivot pin or bolt 42, whereby the composite panel 32 is pivotally secured in place to swing laterally. The side 80 wall or partition 21 of the compartment is shown preferably provided with a bracket or reinforcing channeled plate 43 adapted to receive the pivot bolt 42, see Figures 8 and 9; and the side wall or partition 21 at 90 this point is preferably reinforced by the stud or bar 44 extending to the bottom of the compartment.

The channel members or rails 36 of panel section 32 are each provided with a channel member or section 45, see Figures 10 and 11, of suitable length and provided in one side or leg thereof with a slot or longitudinally cut-away portion as at 46, which receives a pin or projecting lug 47, secured at a predetermined point on the adjacent part of a side frame 48, which may be of the Z-bar construction, of which two are employed, shown more clearly in Figure 10, and provided with the panel 49; the side members 105 or frame 48, providing a snug weather-proof relation with the channel members or rails 36, while at the same time permitting the frame 48 to freely slide in the channel members or rails 36 without binding.

The upper edge of the slideable panel 49 is preferably provided on its outer side with the Z-bar strip 50 adapted to overlap the upwardly disposed edge of a somewhat similar strip 51 secured at the lower end and inner side of the bowed panel 32 (see Figure 10) to provide a weather-proof connection between said panels when panel 49 is in its lowered position at which time the panel 49 will be resting on the ledge of sill member 29, as shown in Figure 2, thus completely closing the sleeping compartment on the outer side thereof against the admission of air or rain. The upper ends of the side frame 48 are each shown provided with a 115 cord or chain 52 which leads upwardly over pulley 39 at the upper ends of the swinging wall section, thence inwardly along the side walls or partitions 21 into a suitable opening in the side of the jamb 20 and over a 120 125 130

pulley as at 53, located within the jamb; while the end of the chain or cord 52 is provided with a suitable counterweight 54, which is adapted to counterbalance the sliding elements or sections of the wall.

Pivotedly secured at 55 to the reenforcing stud or strip 44 of the side wall or partition is a locking link or lever 56, whose opposite end extends along the outer edge or side of the channel member or rail 36 of the panel 32, (see Figure 3) and this end of the link or lever is pivotally secured to the slidable channel member 45 by means of the bolt 57 which extends through the slot 37 in the side rails or members 36 of the swinging panel 32. The pivotal points of the lever 56 are so arranged relative to the inclining swinging wall section that they will be substantially on "dead center," when the section has been swung into either of its two extreme positions, and thus lock the swinging section or panel in its adjusted position.

The wall is normally in the outwardly swung position shown in full lines in Figure 2 and also in two of the divisions or sections of the multiple of sleeping compartments shown in Figure 1, in which position of the wall, the bed is exposed to and made accessible from the main room or apartment of the building; while daylight is admitted to the compartment and therefore to the room through the windows carried by the swinging wall. The occupant while reclining on the bed or couch may admit air from the exterior by merely sliding the panel 49 upwardly to a slight extent, as shown in the third compartment from the left in Figure 1, without releasing the locking lever 56, so that the wall section will remain in its outwardly swung position shown; the sliding of panel 49 being readily accomplished because of the counterbalance 54 secured thereto and the easily slidable connection between the frame members 48 and the channel rails 36. If the occupant desires to sleep entirely in the open this may readily be accomplished by moving the panel 49 upwardly until the lug or pin 47, carried by the frame members 48, reaches the upper end of the slot or cut-away portion 46 in sliding channel member 45, which will cause the members 45 to also slide upwardly in the channel rails 36 and thereby carry the pivoted ends 57 of the lock-levers 56 upwardly with them; such upward movement of the pivoted ends 57 of the levers 56 being possible by reason of the slots 37 in the sides of the channel rails 36 of the upper panel sections 32. This will cause the levers 56 to be moved off "dead center" and at the same time induce the upper panel section 32 to swing inwardly through the arc of a vertically disposed circle as shown in dotted lines in Figure 2. The lower sliding panel

49 and its sliding track will be maintained in raised position by the weights 54, as shown in dotted lines in Figure 2, and therefore in a sufficiently elevated position swing across the occupant of the bed or couch 26. In order that a proper stop for, and more or less tight connection, may be effected between the swinging frame and the side walls or partitions 21, I show the side walls or partitions provided with the

inclined angle irons or strips 58, see Figure 2, which will form abutting relation with the side rails of the swinging section when the latter has been swung to its extreme inward position as indicated in Figure 2, at which time the occupant may lower the sliding panel 49 so as to prevent draughts across the bed and at the same time prevent chilling of the main room or apartment. In order that the panel 49 may be readily manipulated, I show it provided with the grasp or stop 63, see Figure 2. Upon lowering the sliding panel 49 to its maximum lowered position, the lug or pin 47 will ride lengthwise of the slot or cut-away portion 46 of channel members 45 and engage with the lower end of the slot or cut-away portion, thereby causing the channel member 45 to be moved downwardly. Such downward movement of the channel member 45 will carry the pivoted end 57 of locking lever 56 downwardly until it is substantially on "dead center" with its pivotal point 55, while the lower end of the sliding panel 49 will engage with the ledge of the sill portion 31^a of the bracket or rail 31, thereby not only completely closing the opening into the room but also locking the swinging wall section in its inwardly swung position.

A series of sleeping compartments may be arranged end to end as shown in Figure 1, adjacent compartments separated by wall or partition 21 which may extend slightly above the roof sections 22 of the respective compartments, as shown in Figures 1, 4 and 5, in which event I prefer to employ means, somewhat as shown in Figures 4 and 5, whereby to provide a water-proof construction. The means employed, as an exemplification, consist of the sheet metal member 59 adapted to extend the full width of the roof-sections 22 and bent into channel form with the side disposed beneath the roof-section 22 bent upwardly as shown at 59^a into contact with the lower side of the roof-section; similar channel members 59 being disposed on opposite sides of an intermediate wall or partition 21 and bolted together as at 60 in Figure 5 at a point above the roof portion 22; the open side of the channel being disposed away from the partition or wall 21 in order to enable access to the bolts and nuts. After the bolts and nuts have been secured in place, I in-

sert the angularly bent strip 61 into place, as shown in Figure 5, and then encase both members by the outer channel strip 62 which may be slid into place from one end of the members 59 and 61 thereby completely enclosing the joints and providing a watershed connection. The end wall or partition 21 of the compartment may likewise be provided with the enclosing channel member 59 on what may be termed the inner side of the partition or wall; while the outer side of the wall or partition merely receives the channel member 62^a, substantially similar to the channel member 62, except that the leg or side disposed to the outer side of the wall or partition has its end bent inwardly into juxtaposition with the wall or partition as shown at 62^b in Figure 4. The members just described, not only seal the joints between the roof-sections and the walls or partitions and enclose the bolts and nuts, but they also act as supports and reinforcing members for the roof-sections 22. Where a number of compartments are to be arranged end to end, as shown in Figures 1 and 3, the pivot points 55 may extend entirely through the reinforcing strips 44 as well as the partitions 21 and constitute the pivotal points for the lock levers 56 on both sides of the wall or partition. Likewise the pivotal points 42 may be disposed through the wall or partition and through the reinforcing channeled plates 43 on opposite sides of the wall or partition and through the upper ends of the side rails or members 36 of the swinging panels or sections of both compartments, as shown in Figure 9. In Figure 1 and at the left hand end thereof, the swinging wall is shown in its inwardly swung position, thereby exposing the bed or couch to the exterior of the building.

I have shown what I believe to be the simplest embodiment of my invention and have described the same in terms which are employed as terms of description and not as terms of limitation, as structural modifications are possible and may be made without, however, departing from the spirit of my invention.

What I claim is:—

1. In a building construction, a structure having one side open, a wall for said open side comprising a swinging section and a slidable section, said slidable section being adapted to be slid upward onto and carried by said swinging section, and locking means whereby the swinging section is locked in its outwardly and inwardly swung positions, said locking means being automatically moved into and out of locking position by said sliding section.

2. In a building construction, a structure having one side open, a wall for said open side comprising an upper window-carrying

section pivoted at its upper end to swing laterally toward opposite sides of the vertical plane of said pivotal point, a sliding section carried by the first mentioned section, a locking lever pivoted at one end to the side wall or partition of the structure while the other end has a sliding pivotal relation with said swinging section, and means intermediate of said sliding pivotal connection and the slidable section whereby said pivotal connection of the locking lever is controlled by movement of said sliding section.

3. In a building construction, a structure having one side open and provided with a bed, supporting rails for said bed adapted to constitute sills disposed longitudinally along opposite sides of the bed, a wall for said open side comprising an upper swinging section adapted to swing through the arc of a vertically disposed circle, a slidable section carried by said swinging section and adapted to rest on the sill portions of said supporting rails when in lowered position, and locking means operable through movement of the slidable section whereby said wall is locked in its outwardly and inwardly swung positions.

4. In a building construction, a structure provided with a bed and having an open side, a wall pivotally secured at its upper end to swing toward opposite sides of the bed, a portion of said wall being adapted to slide upwardly and to be carried by the other portion of said wall, a locking lever disposed at the end of the swinging wall and operatively connected therewith, and means controlled by said slidable portion whereby said locking lever is automatically controlled through movement of said slidable portion.

5. In a building construction, a structure provided with an open side, a wall for said open side comprising an upper window-carrying portion pivoted at its upper end to swing laterally and provided at its ends with slide-ways, a lower slidable portion adapted to slide in said slide-ways of the upper portion, slidable elements, intermediate of the slideways of the upper portion and said lower portion, adapted to be controlled by the position of said lower portion, and locking levers pivotally secured to the end walls of the structure and to said slidable elements whereby the wall is locked in its outwardly or inwardly swung positions, said slidable elements with the adjacent pivoted ends of said locking levers being controlled by the position of said lower slidable portion.

6. In a building construction, a structure provided with end walls and an open side, a swinging wall comprising an upper section pivotally secured to said end walls to swing laterally and provided with counter-weight cord receiving pulleys adjacent the upper end, a sliding track mounted in each end of said upper section, a lower sliding section

slidable in said sliding tracks, counter-
weights for the lower sliding section flexibly
connected thereto across said pulleys of the
upper section, a locking lever pivotally se-
cured to each end wall and to each sliding
track, and means intermediate of the lower
sliding section and said sliding tracks where-
by the latter with the attached ends of said
levers are automatically shifted through
movement of said sliding section.

7. In a building construction, a structure
having one side open, a wall for said open
side comprising an upper section and a lower
section, the upper section being pivotally
mounted and swung laterally, while the
lower section is slidably mounted on the
upper section, and means whereby said wall
is locked in its outwardly and inwardly
swung positions, said means being moved
out of locking position when said lower sec-
tion is slid upwardly beyond the prede-
termined point.

8. In a building construction, a struc-
ture having one side open, a wall for said
open side comprising an upper section and
a lower section, the upper section being
pivotally secured at its upper end to swing laterally,
while the lower section is slidably mounted
on the upper section and carried thereby,
locking means pivotally secured at the ends
of said structure and having operative rela-
tion with said lower section, and means
intermediate of said lower section and said
locking means whereby the latter is actuated
when said lower section reaches predeter-
mined points in its upward and downward
movements.

9. In a building construction, a structure
having one side open, a wall for said open
side comprising an upper section and a
lower section, the upper section being pivot-
ally secured at its upper end to swing laterally,
while the lower section is slidably mounted
on the upper section, and a pair of lock-
ing levers pivotally secured at both ends of the struc-
ture adapted to hold the wall in its out-

wardly and inwardly swung positions, said
levers being adapted to be moved out of
locking position when said lower section
reaches a predetermined point in its up- 50
ward movement.

10. In a building construction, a struc-
ture comprising end walls and intermediate
walls or partitions spaced apart to provide
a plurality of open sided compartments, 55
each having a separate roof portion, means
removably secured to the walls or parti-
tions whereby the roof portions are support-
ed in place and moisture proof connections
provided, a wall for the open side of each 60
compartment consisting of a pivoted upper
section adapted to swing toward opposite
sides of the respective compartment, a lower
section slidably mounted on the upper sec-
tion, and locking levers pivotally secured to each end 65
wall or partition of the respective compart-
ments whereby the side wall is locked in its
outwardly or inwardly swung positions, said
locking levers being controlled by the pos-
ition of said lower section relative to the 70
upper section.

11. In a building construction, a struc-
ture comprising end walls and intermediate
walls or partitions to provide a series of
open sided compartments, the walls or parti-
tions at their outer edges and at an inter-
mediate point being provided with abut-
ting rails, a wall for the open side of each
compartment consisting of a pivoted upper
section adapted to swing laterally into jux- 75
taposition with said rails, a lower section
slidably mounted on the upper section, locking levers
pivotally secured to the end walls or partitions for
locking said side wall in place, and means
intermediate of said levers and the lower 80
section whereby the position of said levers
is controlled when the lower section reaches
a predetermined point in its movements.
